INSULATOR

Howard P. Seelye, Birmingham, Mich.

Application April 26, 1938, Serial No. 204,397

4 Claims. (Cl. 174—154)

The invention to which the following description relates is that of an improved electrical insulator of the type customarily used for supporting electric wiring. Such insulators are widely used where wiring is brought in from a transmission line to a building or the like. Such wiring imposes considerable stress upon the insulator support not only in the direction perpendicular to its base or surface of attachment, but in many instances at wide angles thereto. In such "dead-ending" an unbalanced strain or tension of considerable quantity is imposed upon the insulator.

Porcelain is an admirable material with which to make such an insulator and in my prior Patent No. 2,950,898, I have shown one form in which such an insulator may be made. There are, however, some conditions in which it is desired to utilize the maximum strength of porcelain as developed when it is placed under compression instead of tension. Consequently, the present invention provides means by which the porcelain of the insulator where it holds the conductor is itself placed under considerable compression with consequent increase in strength.

One of the objects of my invention is to provide an insulator having the porcelain maintained under compression with the several metallic members satisfactorily shielded from the electric conductor and protected from exterior exposure.

A further object of my invention is to provide a screw-threaded attaching member by which the insulator may be fastened to its support without the use of special tools and without imposing exceptional strain upon the porcelain material itself.

Among the objects of my invention is to provide an improved anchor between this screw-threaded fastening and its supporting plate.

Likewise as an incident of my invention my insulator is so designed that its base will be brought up into a tight fit against the support completely shielding the metallic attaching means from exposure or the likelihood of corrosion or current leakage.

Incidental to my design it will be found that the assemblage of the device is rendered more simple and efficient. The above and other advantages will be apparent from the following description of the preferred form of my invention as illustrated in the drawings in which:

Fig. 1 is a side elevation, partly in section, of the improved service insulator;

Fig. 2 is a plan view of the same;

Fig. 3 is a vertical section on line 3—3 of Fig. 2;

Fig. 4 is a perspective view of the U-bolt and plate;

Fig. 5 is a horizontal cross-section on line 5—5 of Fig. 1;

Fig. 6 is a side elevation partly in section, of a modified form;

Fig. 7 is a vertical section on line 7—7 of Fig. 6 and

Fig. 8 is a horizontal cross-section on line 8—8 of Fig. 6.

The insulating body member 11 of my improved insulator is formed of a single piece of porcelain forming a knob having the desired exterior form and a flat circular base 12. The exterior of the body member may be of any suitable form facilitating ease in manufacture and serviceability. For this purpose the top may have a transverse saddle 13 and a peripheral groove 14 may be used as indicated on the drawings.

The electric conductor, wire cable or the like passes through the central transverse passageway 15.

The base 12 has a diametric recess 16 extending in a plane at right angles to the passageway 15. This recess does not intersect the side walls of the body member but on the contrary is completely surrounded by the base 12. A central depression 17 appears back of the recess 16 for the purpose of holding the head of the attaching screw.

Surrounding the passageway 15 and concentric thereto for half of its periphery is a deep groove 17. The ends of the groove 17 become tangential holes 18 which pass through the body member and into the base recess 16 as shown in Fig. 1.

The recess 16 in the base forms a seat for a cross bar or plate 19. This plate is of less thickness than the depth of the groove 16 so that when the plate is drawn up against the body member there will be a substantial clearance between the plate and the plane of the base 12. The plate 19 has a central opening 20 through which the shank of the attaching screw passes. This opening 20 may be irregular in shape and in Figs. 4 and 5 is shown to be square so that it may be used to anchor or interlock the shank of the screw. The plate 19 is also provided with openings 21, 21 registering with holes 18, 18 of the body member 11. This plate may also be made round or oval.

A strap, band, rod, fillet or the like 22 is provided of ductile metal preferably in the form of a round copper rod. This strap fits in the groove

17 with its ends passing through the holes 18 and into the recess 16. The ends 23 of the strap 22 pass through the plate 19 and are headed, riveted or swaged into the plate or bolted thereto so that the latter can be drawn tightly up against the body member 11.

It is to be understood that prior to the attachment of the strap 22 the wood screw 24 has been inserted through the plate 19 with its head 10 25 above the plate 19 and received in the depression 17.

The shank of the wood screw has diametric ribs 26 which anchor into the corners of the square opening 20 and prevent relative rotation 15 of the screw and plate. To facilitate assembly and insure the proper positioning of the parts, these ribs 26 may be formed as tangs which are bent over the lower face of the plate 19 as shown in Fig. 1.

20 In Figs. 6, 7 and 8 an alternative form is shown in which the base plate is in the form of a channel bar 27 having its recess opening upwardly. The use of such a channel member permits the use of a wood screw having the customary square or other polyhedral head 28. As shown in Fig. 8 this head 28 fits closely within the side flanges 29, 29 of the channel member 27. In this manner the screw is held firmly against relative rotation.

30 In the assembly of this insulator, the wood screw is applied to the base plate either as indicated in Fig. 1 or Fig. 6. The ductile metal strap 22 is passed beneath the base plate 19 or 27 and the ends 23 upset, headed or otherwise swaged. This tends to bring the head of the screw into contact with the body member and to lift the bottom surface of the base plate 19 or 27 above the plane of the base 12.

An insulator of this type is readily used as it 40 can be driven with considerable force against the support without damage to itself. It may then be rotated causing the torsion to be applied to the screw through the extended base plate 19 or 27. This avoids reliance upon the porcelain for localized torsion. In the final tightening 45 of the screw the porcelain base 12 is brought against the support and the porcelain body member thus placed under preliminary compression. When the wire conductor or cable is attached the porcelain of the passageway 15 is placed under 50 further compression resulting in the greatest strength and durability. The direction of approach of the conductor is relatively unimportant and has slight if any effect upon the 55 strength of the insulator.

While I have shown the preferred form of the invention it is to be understood that this has been done by way of example only and that minor changes in the design and material may be made 60 without departing from the scope of the invention as defined in the following claims.

What I claim is:

1. An insulator having an insulating body member with a base with a flat surface and a transverse wire-holding passageway, a groove in the member above and concentric with the transverse passageway, openings through the member on each side of the transverse passageway connecting the groove with the base, a diametric recess in the base extending between the openings but not through the sides of the member, 10 a plate in said recess spaced wholly above the plane of the base, a strap in said openings and groove with its ends fastened to the plate, a central irregular opening through the plate, a screw extending through said last named opening and means on the shank of the screw for interlocking with said opening. 15

2. An insulator having an insulating body member with a base with a flat surface and a transverse wire-holding passageway, a groove in 20 the member above and concentric with the transverse passageway, openings through the member on each side of the transverse passageway connecting the groove with the base, a diametric recess in the base extending between the openings 25 but not through the sides of the member, a channeled plate in said recess, a strap in said openings and groove with its ends fastened to the plate, a central opening through the plate, and a screw extending through said opening, said 30 screw having a polyhedral head anchored in the channel of said plate.

3. An insulator having an insulating body member with a base with a flat surface and a transverse wire holding passageway, a groove in 35 the member above and concentric with the transverse passageway, openings through the member on each side of the transverse passageway connecting the groove with the base, a diametric recess in the base extending between the openings 40 but not through the sides of the member, a plate in said recess and spaced wholly above the plane of the base, a strap in said groove and openings with its ends fastened to the plate, and a screw anchored in said plate. 45

4. An insulator having an insulating body member with a base with a flat surface and a transverse wire holding passageway, a groove in the member above and concentric with the transverse passageway, openings through the member 50 on each side of the transverse passageway connecting the groove with the base, a diametric recess in the base extending between the openings but not through the sides of the member, a plate in said recess and in contact with the 55 side walls of the recess, a strap in said groove and openings with its ends fastened to the plate, and a screw anchored to said plate.

HOWARD P. SEELYE. 60
